CLAIM

The ornamental design for a canopy, as shown and described.

DESCRIPTION

FIG. 1 is a left front isometric view of a first embodiment showing my new design;

FIG. 2 is a front view of the canopy of FIG. 1;

FIG. 3 is a right side view;

FIG. 4 is a left side view;

FIG. 5 is a back view;

FIG. 6 is a top view;

FIG. 7 is a bottom view;

FIG. 8 is a fragmentary bottom view of a second embodiment, the front, sides, back and top views being substantially identical to those views of the canopy shown in FIGS. 1-6; FIG. 9 is a fragmentary bottom view of a third embodiment, the front, sides, back, and top views being substantially identical to those views of the canopy shown in FIGS. 1-6; FIG. 10 is a fragmentary bottom view of a fourth embodiment, the front, sides, back, and top views being substantially identical to those views of the canopy shown in FIGS. 1-6;

FIG. 11 is a fragmentary bottom view of a fourth embodiment, the front, sides, back, and top views being substantially identical to those views of the canopy shown in FIGS. 1-6;

FIG. 12 is a fragmentary bottom view of a fourth embodiment, the front, sides, back, and top views being substantially identical to those views of the canopy shown in FIGS. 1-6;

FIG. 13 is a fragmentary bottom view of a fourth embodiment, the front, sides, back, and top views being substantially identical to those views of the canopy shown in FIGS. 1-6; and,

FIG. 14 is a fragmentary bottom view of a fifth embodiment, the front, sides, back, and top views being substantially identical to those views of the canopy shown in FIGS. 1-6.
